UNITED STATES PATENT OFFICE.

HIRAM STEVENS MAXIM, OF LONDON, ENGLAND.

EXPLOSIVE PROJECTILE.

SPECIFICATION forming part of Letters Patent No. 738,621, dated September 8, 1903.

Application filed July 16, 1901. Serial No. 68,539. (No model.)

To all whom it may concern:

Be it known that I, HIRAM STEVENS MAXIM, chevalier of the Legion of Honor, civil and mechanical engineer, a subject of the King of Great Britain, residing at 18 Queens Gate Place, in the county of Middlesex, have invented certain new and useful Improvements Relating to Explosive Projectiles, of which the following is a specification.

10 This invention has reference to explosive projectiles, and particularly to armor-piercing explosive projectiles that are intended for large and heavy guns of about ten-inch caliber and upward.

15 Several years ago I devised and patented, under British Patent No. 17,252 of 1887, means for preventing the premature explosion of an explosive projectile on shock of discharge by employing what is termed a "delayed-action" fuse—that is to say, a movable detonating charge or fuse placed in a tube extending outside the projectile—so that said fuse normally lies at a distance so far from the projectile that a premature explosion of the fuse would only disrupt the tube and not explode the main charge in the projectile. On impact of the projectile the fuse was released from its distant position relatively to the projectile and then traveled by 25 its own momentum toward and finally struck a firing-pin within the projectile, thus detonating the main charge.

20 One of the objects of my present invention is to make the aforesaid tube or chamber project into the space containing the explosive charge and to provide it with means, such as a comparatively heavy shutter or slide, which is normally held by a spring or other appropriate device in a position between the 25 movable fuse and the firing-pin at the inner end of said tube. The said shutter or slide is so formed that it will move from this position against the resistance of the said spring by the action of centrifugal force due to the 30 revolution of the projectile during its flight from the gun, thereby leaving a free path for the fuse to advance and reach the firing-pin on impact of the projectile. The said shutter or slide is also provided with means, 35 such as a catch or catches, so arranged that when the slide is shifted out of the path of the fuse, as aforesaid, it is maintained in that position.

35 A projectile having a fuse of this description may be handled with the greatest safety, because until the projectile is fired from the gun there is no direct communication between its fuse and the firing-pin. When, however, the projectile is fired from the gun, the said communication is opened and remains open during the flight of the projectile. Therefore when the projectile strikes the armor-plate and commences to penetrate it (thereby diminishing the velocity of the projectile) the fuse continues its forward movement, and when or after the projectile 40 has passed through the armor-plate the fuse reaches and its detonator collides with the firing-pin, thus exploding the fuse, which in turn detonates the main charge in the projectile. If a projectile provided with a delayed-action fuse of this kind should have its fuse prematurely detonated by the shock of discharge while the projectile is still in the gun, only the external portion of the tube or chamber or that part containing the fuse will be 45 disrupted, the shutter or slide preventing disruption of the internal part of the tube or chamber and detonation of the main charge in the projectile. In such a projectile also the fuse may be readily and safely detached 50 for inspection at any time by the removal of a screw plug or cap at the outer end of the external portion of said tube or chamber. According to a modification of my invention and where the projectile is large enough to 55 permit thereof I may dispense with the external projecting portion of the aforesaid tube or chamber and arrange said fuse and said shutter or slide in a cavity in the base of the projectile leading to the said internal tube or 60 chamber, and in this case I may provide the projectile with a detachable base-plate of such a shape that there will be formed an isolating-chamber completely inclosing the outer end of the fuse, into which chamber in the 65 event of a premature detonation of the fuse taking place the resulting gases and fragments of metal will be received and contained without entering the charge-chamber of the gun. In some cases I make the aforesaid 70 base-plate capable of deformation or movement toward the base of the projectile under the pressure of the powder-gases in the gun on firing, so as to squeeze and force outwardly

against the bore of the gun an obturator-ring, as is well understood, the said obturator-ring being constructed and arranged to operate as hereinafter described. A thin ring of comparatively soft metal, such as brass or copper, may also be interposed between the face of the obturator-ring and the base-plate, the edge of said metallic ring extending beyond the periphery of said base-plate, so that on the firing of the gun the edge of the metallic ring, which is not covered by the base-plate, will be bent rearwardly and cover the peripheral edge of the base-plate with a suitable metal to prevent its injuring the bore of the gun.

In order that my said invention may be fully understood and readily carried into practice, I will describe the same more fully with reference to the accompanying drawings, in which—

Figure 1 is a central longitudinal section, and Figs. 2 and 3 are transverse sections thereof on the line 5 5, showing one form of my explosive projectile in which the shutter or slide is in two portions adapted to open by sliding apart. This form is suitable for projectiles of eight or nine inches diameter. Fig. 2 represents the shutter closed, and Fig. 3 represents it open. Fig. 4 is a central longitudinal section of another form of the projectile provided with a two-part shutter and in which there is no rearwardly-extending tube or chamber for the fuse and only a short tube extending into the explosive charge of the projectile. This form of the projectile is especially suitable for charges of black powder. Fig. 5 is a detail sectional view showing the position which the parts therein illustrated approximately assume after firing. Fig. 6 is a cross-section on the line 7 7 of Fig. 4.

In all these figures like letters of reference indicate similar parts.

A is the body of the projectile, containing the explosive charge.

B is the fuse. C is the tube, that extends from the chamber wherein said fuse is housed into the space of the projectile containing the said explosive charge. C' is the firing-pin, located at the inner end of said tube and against which the detonator of the fuse B strikes when said fuse is released and permitted to travel independently on impact of the projectile. D is the shutter or slide for normally keeping said shutter closed.

E is the base-plate or disk.

F is the obturator-ring, G the driving-band, and H the wall of the gun.

Referring first more particularly to Figs. 1 to 6, the fuse B is situated in a chamber a, extending rearwardly from a screw-threaded block A', that closes the opening in the base of the projectile through which the explosive charge is introduced. The outer end of the said chamber is closed by a screw-plug a², which is furnished with a hexagonal or other suitably-shaped head for enabling it to be readily removed for access to be had to the

fuse when necessary. The aforesaid screw-threaded block A' is formed with a lateral cavity a³ for the reception of the shutter or slide D, the said cavity being closed by the screw-flange C² of the tube C, which screws into the forward or inner face of the said block A', so that the shutter can be placed in its cavity a³. The said flange C² has holes c c or is otherwise formed to enable it to be screwed in place by means of a suitable tool. The tube C lies coaxial with respect to the chamber a and the fuse B, and the shutter D is normally kept in its closed position—that is to say, in the path of the fuse—by means of a light spring d. The said shutter is of considerable thickness and weight, and the cavity in which it is situated is radial with respect to the axis of the projectile. The said spring is sufficiently strong to keep the shutter in its closed position under all ordinary circumstances attending the handling of the projectile; but on the firing of the projectile from the gun and its flight through the air the said spring will give way under the centrifugal force acting on the shutter, and so permit the latter to assume its outward or open position, and thereby leave a clear passage for the fuse to advance toward the firing-pin C' after the projectile strikes an object, as aforesaid. In order to retain the shutter in its open position, catches in the form of spring-bolts d¹ are provided for engaging with corresponding recesses a⁴. These spring-bolts may be located in the shutter D or in the wall of the cavity a³. d² is a central pin or core extending through said spring d for preventing the latter from becoming displaced or deformed by the shock of discharge. The shutter is formed with a cavity or hole d³ for the inner end of said pin to enter as the shutter assumes its open position. I may employ springs of different shape to that represented in the drawings. For instance, curved-blade springs may be used instead of the helical springs shown. It will be obvious that so long as the shutter remains closed the fuse cannot advance along the tube C nor reach the firing-pin C', and that in the event of a premature explosion of the fuse on shock of discharge the said heavy shutter will prevent the shock of such explosion from being transmitted to the main charge of explosive in the projectile, such premature explosion of the fuse only causing the chamber a containing it to be disrupted or destroyed, as represented in Fig. 2. The screw-plug a² is furnished with a circular flange a⁵, which enters a corresponding circular recess in the end of the chamber a and prevents the threads of the said plug becoming corroded by moisture, so that said plug can always be easily removed when required. The shutter D is made in two parts, which are held together in a position to close the tube C by means of two catches or spring-bolts d⁴, these two parts of the shutter being adapted to separate and open, as shown in

Fig. 3, under the action of centrifugal force during the flight of the projectile, in which position said parts are retained by the catches or spring-bolts engaging with the recesses d^5 . 5 These spring-bolts d^4 are normally prevented from entering their recesses d^{xx} and releasing the shutter by pins d^x , of copper or other soft metal, located in the said recesses. On shock of discharge the said bolts fully enter 10 their recesses d^{xx} by compressing their springs and collapsing the pins d^x . By the time the springs of said bolts (which springs are light ones) react to force the bolts forward again the projectile has left the gun and centrifugal force has opened the shutter, thereby bringing the recesses d^5 of the shutter opposite the bolts, so that as they advance they enter the same and lock the shutter in its 15 open position. In this case also I have represented two obturator-rings $F F^x$, the former of which is made of very hard vulcanized fiber or woodite and the latter of a softer form of such material.

The arrangement illustrated in Figs. 4 to 25 6 is similar to that illustrated by Figs. 1 to 3, with the exception that the tube C is made shorter, and therefore needs no further description.

The projectile is, as already stated, especially intended for use with explosive charges 30 of black powder.

What I claim, and desire to secure by Letters Patent of the United States, is—

1. In an explosive projectile, the combination 35 of a delayed-action fuse, of a shutter adapted to normally lie between the detonator of said fuse and its firing-pin, of a bolt for retaining said shutter in this position until acted upon by the shock of discharge, and of 40 a light spring tending to keep the bolt pressed forward and operating to return said bolt and reengage it with the shutter by the time the latter has been opened by the action of cen-

trifugal force during the flight of the projectile from the gun, substantially as described. 45

2. In an explosive projectile, the combination of a delayed-action fuse, and of a shutter adapted to normally lie between the detonator of said fuse and its firing-pin, of a bolt for retaining said shutter in this position until acted 50 upon by the shock of discharge, of a soft-metal pin located behind said bolt for normally preventing it from being shifted but which becomes displaced by the movement of the bolt on shock of discharge, and of a light 55 spring tending to keep the bolt pressed forward and which operates to return said bolt and reengage it with the shutter by the time the latter has been opened by the action of centrifugal force during the flight of the projectile from the gun substantially as described. 6c

3. In an explosive projectile, the combination of a delayed-action fuse situated in a chamber at the base of the projectile, of a firing-pin situated within the body of the projectile at a point remote from said fuse and opposite its detonator, of a shutter normally lying between said fuse-chamber and said firing-pin until shifted by centrifugal force, of a detachable dome or dished base-plate forming an isolating-chamber around the rear portion of the fuse-chamber, of a light metallic 65 detachable cover for closing the outer end of said fuse-chamber, and of a pin for connecting the fuse to said detachable cover and adapted to be severed to release the fuse on shock of impact substantially as described. 70

In testimony whereof I have hereunto set my hand, in presence of two subscribing witnesses, this 3d day of July, 1901. 8c
